UNITED STATES PATENT OFFICE.

DAVID H. SHAPIRO, OF MONTREAL, QUEBEC, CANADA.

COLLAPSIBLE SHIPPING-PACKAGE.

1,141,076.

Specification of Letters Patent.

Patented May 25, 1915.

Application filed December 21, 1914. Serial No. 878,385.

To all whom it may concern:

Be it known that I, DAVID H. SHAPIRO, a citizen of the Dominion of Canada, and resident of the city of Montreal, in the 5 Province of Quebec and Dominion of Canada, have invented certain new and useful Improvements in Collapsible Shipping-Packages, of which the following is a full, clear, and exact description.

10 This invention relates to improvements in knock-down shipping packages for clothing and the like, and the object is to provide a simple and convenient shipping package which may be manufactured and sold at 15 less cost than the boxes ordinarily used for such purposes.

A further object is to provide a shipping package which may be stored in knock-down form and erected into operative form 20 more quickly and easily than many types of box.

25 A still further object is to provide a shipping package which will hold the garments therein in better form and preclude movement of the garment within the package, which cannot be overcome in the ordinary box without the use of a filling.

Another object is to provide a better proportioned package and one which may be 30 carried much more conveniently than the ordinary box.

Still another object is to provide a package by means of which the garment may be packed in better condition to withstand 35 transportation without wrinkling or creasing, and at the same time packed more quickly than is possible with the ordinary box.

With the foregoing and other objects in 40 view, the device consists essentially of a single sheet of material creased for folding to form a complete inclosure for the contents having two of its side walls vertical, and the remaining two sides inclined toward 45 one another. The device is provided with interengaging locking means adapted to engage one another, as nearly as possible automatically during folding of the sheet around the article to be packed, so that no 50 unnecessary movements are required.

In the drawing which illustrates the invention:—Figure 1 is a plan view of one end of a blank. Fig. 2 is a similar view of a slightly different form. Fig. 3 is a partial 55 perspective view of the device as made up in the factory. Fig. 4 is a partial perspec-

tive view of the device in knock down form. Fig. 5 is a partial perspective view of the device partially closed. Fig. 6 is a perspective view of one end of the device in closed 60 position.

It will be understood that there is no pre-ferment between the forms shown in Figs. 1 and 2, and also that there is no real difference, the distinction between the two being 65 merely that incident to a slight alteration of proportion. All such distinctions are considered as contemplated in the present invention, and therefore only one has been shown. It must also be understood that the 70 invention is in no way limited to or by the particular arrangement of fastening devices shown, as this arrangement is also largely dependent upon the proportions of the device. As a package for clothing, particu- 75 larly coats and waists, the device is designed for co-operation with garment forms such as described in my former applications, Ser. Nos. 836,364, 855,875 and 872,381.

Referring more particularly to the draw- 80 ings, 1 and 2 show fragments of a sheet of material divided by creases 11 into a central or bottom portion 12, a pair of side portions 13, cover portions 14, and end or remaining side portions, 15, 16 and 17, connected re- 85 spectively to the central portion, the side portions and the top portions. The central or bottom portion is rectangular in shape and of suitable proportion, and is connected on two opposite edges with suitably propor- 90 tioned side portions 13 and on the two oppo- site remaining edges with the ends or re- 95 maining sides 15. Each end 15 has its free edge 18 shorter than the edge in attachment with the bottom portion at the fold and par- 100 allel therewith or otherwise, as required by the nature of the article to be packed, and as indicated in dotted lines, Fig. 2. The two remaining free edges 19 are convergent from the fold toward the edge 18 as shown, but 105 it is obvious that these edges may be divergent or parallel, if the nature of the article to be packed so requires. Each end is also pro- 110 vided with a suitably disposed tongue 20 formed integral therewith. Each of the side 105 portions 13 is provided with an end member 16 having the edge 21 thereof facing the edge 19 of the end portion 15 cut as nearly as practicable at the same angle as the edge 19, but in the opposite direction. The oppo- site edge 22 of this end tongue is preferably cut in line with the fold between the parts

13 and 14, while the end edge 23 is cut at the same angle as the end edge 18 but in the opposite direction. Each tongue 17 has its edge 24 cut at an angle to the edge 22, which 5 approximately quadrisects the angle between the edges 19 and 21, and its edge 25 cut at the same angle as the edge 18 but in the opposite direction. The width of the flaps 17 depends upon the width of the top portions 14 which are made as desired. The adjacent portions of the end tongues 16 and 17 are suitably perforated as shown at 26, to indicate the location of a wire stitch or the like for fastening the portions 16 and 17 in 10 overlapping relation. Each portion 16 is in addition provided with a crease 27 extending from the intersection of the edges 22 and 24 at the same angle as the edge 24. The proportion of the side and top portions 13 and 14 obviously depends entirely upon the 15 depth of the box and the width of its top. Wherever possible, the top portions 14 are kept a trifle narrower than the side portions 13, so that in knock-down condition, the top 20 portions 14 may be folded on the side portions 13, and the two upon the bottom portion 12. Wherever the box is comparatively shallow, unless the sides are greatly inclined, one or both of the top portions 14 will be 25 wider than the side portions, as shown in Fig. 1, so that the double folding in knock-down condition is precluded. Fig. 2 shows a proportion permitting the double folding. The blank when provided in the factory 30 with stitches 28 passed through the apertures 26, assumes the angular form shown in Fig. 2. By means of the folds 27, the end portions 16 and 17 may be folded in upon the portions 13 and 14, and the portion 14 35 folded on the portion 13, and if proportion permits, the two portions folded upon the bottom portion, as shown in Fig. 4. This is the condition in which the device leaves the factory, either with or without a garment 40 form, designated 29, held in flat condition on the bottom by the folding in of the ends 15 and sides and top 13 and 14.

In packing a garment such as a coat, the wrapper is open to the position shown in 45 Fig. 3, with the exception that the ends 15 are turned to vertical position. The coat is placed lining up on the wrapping sheet, the form 29 inserted therein, and the coat folded over the form, the sleeves being folded 50 over the front of the coat. One side and top portion is then brought to the position shown in Fig. 5 with the outer edge 30 engaging under the tongue 20. The mere movement of the operator's fingers in holding the end 55 portion 15 will flex the same sufficiently to throw out the tongue 20 and the end flap 17 will slide under the tongue with the operation of swinging the top and side to closed position. The other side and top portion 60 are now swung into closed position and the 65

hook 31 slips automatically between the end flaps 16 and 17 of the opposite side and engages under the stitch 28. The closing of the box may be completed by a cord or tape 70 fastened to the bottom or some other suitable part of the box, or separate therefrom.

From the foregoing description, it will be seen that the package requires considerably less material than the ordinary cardboard box used for packing clothing, and 75 may, therefore, be manufactured and sold at a considerably lower cost than ordinary boxes. The operation of placing a garment in the box is performed in less time than required with the ordinary box, where it is 80 necessary to make up the box and cover, fold the garment, place the same in the box, and then fit the box and cover together, whereas in the present device, the making up of the box and folding of the garment 85 therein are almost identical.

It is well known that a garment when folded up either with or without a supporting form is much thicker in the middle, and that therefore when placed in an ordinary 90 box of sufficient depth, there is much waste space at the long edges of the box in which the garment can move around during transport and thus become wrinkled and out of shape. In the present invention, the sloping sides of the box eliminate this waste 95 space and effectually preclude movement of the garment in the box if mounted on any sort of form, and more especially so if mounted on a convex form, such as described 100 in my former patents previously mentioned. Another advantage is that a package of this form is much easier to carry than the ordinary box, as it will slip under the arm without inconvenience or discomfort. This feature is of considerable importance, as it will insure a certain economy to the user by saving 105 of delivery charges, since many customers in a hurry for the garments will consent to carry such a package, who would not 110 consent to carry the ordinary awkward form of box. A further advantage is that the package may be made much wider than the ordinary box, and still effect considerable 115 saving of material, so that coats and the like may be packed flat without unnatural folds. In short, the device provides economy in cost and time for the user, and retains the 120 contents in much better condition, so that the first impression of the recipient opening 125 the package is favorable.

While the end flaps 16 and 17 have been shown and described permanently stitched together, it is obvious that they may be provided with any of the well known forms of 125 hook and slot connections, and that the holding means 20 and 31 may be varied according to circumstances without departing from the spirit of the invention. It will also be understood that although the device has 130

been described only as a wrapper for clothing, it may be constructed in varying sizes, shapes and proportions for packing many other articles which fill only a small part of the boxes in which they are usually packed, such as hats.

I claim—

1. A knock-down box comprising a bottom, ends hingeably connected thereto, compound side and top portions hingeably connected to opposite edges of the bottom, collapsible end flaps connected between the side and top portions normally holding the same in predetermined angular relation, tongues on the ends engageable by the end flaps of one composite side and top portion, and tongues on the end flaps of the second side and top portion engageable between the end flaps of the first side and top portion.
2. A knock-down box, consisting of a bottom, ends, and two cover portions, said cover portions coöperating to form sides and top and being each collapsible upon itself and foldable upon the bottom and collapsible end flaps connected between the side top portions normally holding the same in predetermined angular relation.
3. A container comprising a bottom, hingeably connected ends, sides hingeably connected to the bottom, top members hingeably connected to the sides, end flaps hingeably connected to the sides and to the top members and each having a pair of apertures therein, fastening means inserted

through the apertures holding the end flaps 35 in overlapping relation and the side and top members in angular relation, folds in the end flaps of the side members positioned for the collapsing of the end flaps between the side and top members when folded upon 40 one another, and interlocking means between the ends and end flaps on one side and between the end flaps arranged to hold the package in erected form.

4. A container comprising a bottom, ends 45 hingeably connected thereto, side members hingeably connected to the bottom, a pair of top members one hingeably connected to each side, one of said top members being of less width than the top of the box and the 50 other being of substantially the same width as the top of the box, end flaps on the side members and on the top members, means adapted to hold said end flaps in overlapping relation and the side and top members 55 in predetermined angular relation, tongues on the ends engageable by the end flaps of the narrower top member, and hooks on the end flaps of the wider top member engageable with the end flaps on the opposite side 60 of the package.

In witness whereof, I have hereunto set my hand, in the presence of two witnesses.

DAVID H. SHAPIRO.
